UNITED STATES PATENT OFFICE.

BENJAMIN C. BARTLEBAUGH, OF WHEELING, WEST VIRGINIA.

CONVERTIBLE CHAIR.

1,415,767.

Specification of Letters Patent.

Patented May 9, 1922.

Application filed September 19, 1921. Serial No. 501,729.

To all whom it may concern:

Be it known that I, BENJAMIN C. BARTLEBAUGH, a citizen of the United States, residing at Wheeling, in the county of Ohio and State of West Virginia, have invented certain new and useful Improvements in Convertible Chairs; and I do declare the following to be a full, clear, and exact description of the invention, such as will enable others skilled in the art to which it appertains to make and use the same.

My invention relates to improvements in articles of furniture which may be converted for numerous uses and has reference more particularly to a chair which may be quickly and easily converted for use as a lounge, as a full-length bed, or as a child's bed, the object of the invention being to provide a comparatively simple and inexpensive arrangement of parts for expeditiously producing the required results.

With the foregoing in view, the invention resides in the novel construction and combination of parts, hereinafter described and claimed, the descriptive matter being supplemented by the accompanying drawings.

Figure 1 is a side elevation of a convertible chair constructed in accordance with my invention, showing it in condition for use as a Morris chair with full lines and showing other positions in dotted lines.

Figure 2 is a detail longitudinal sectional view through the bed clothes compartment and associated parts.

Figure 3 is a detail longitudinal sectional view showing the manner of supporting the back section in a horizontal position.

Figure 4 is a side elevation of the invention in condition for use as a child's bed.

Figure 5 is a top plan view with the several parts in the relative relation shown in Fig. 6.

Figure 6 is a side elevation of the invention in condition for use as a full length bed.

Figure 7 is a detail transverse sectional view as indicated by line 7—7 of Fig. 6.

In the drawings above briefly described, the numeral 1 designates a rectangular horizontal platform or base which is preferably supported on casters 2. The base 1 includes a pair of upstanding side-boards 3 between which a seat section 4 is guided, said section 4 being mounted on appropriate rockers 5 which are held in proper position upon the base by suitable lugs 6 engaging keepers 7.

The seat section 4 is preferably in the form of a box to contain bed clothing and this box is provided with a hinged cover 8. The rockers are preferably provided with rubber tires 5a.

A back section 9 is pivoted at 10 to the seat section 4 and may be moved rearwardly to different inclined positions or to the horizontal position shown in Fig. 4. When the back section 9 is in the last named position, its outer end is supported by crossed legs 11 which are self-extensible when the back is swung downwardly and self-contractible when said back is righted. The inner end of the back section 9, when said section is swung to a horizontal position, rests on a wall 12 which extends upwardly from the rear end of the base 1, whereby to prevent any rocking of the seat section 4.

To hold the back section 9 in one of its inclined positions, it may well be provided with a relatively long folding leg 13 (see Figs. 1, 3 and 6).

Straddling the box 4 and pivoted at their front ends thereto as indicated at 14, are two arm-carrying side members 15 having rearwardly extending portions 16 straddling the back section 9 and provided with a plurality of notches 17 forming hooks for co-action with lugs 18 on said back section, whereby to hold the latter in substantially upright position or in one of its inclined positions, when the device is to be used as a chair. Whenever desired, the side members 15 may be swung forwardly and downwardly as shown in Figs. 1 and 6, whereupon bumpers 19 carried by the extensions 16 will rest upon the floor. When now, the back section 9 is swung rearwardly to an inclined position as dotted in Fig. 6, an effective lounge will be provided whereas throwing said back section to the full line position disclosed in Fig. 6 will convert the device into a full-length bed. By merely throwing the back section 9 downwardly without turning the side members 8 downwardly (see Fig. 4), an effective child's bed is provided, side pieces for the bed being formed by said members 15.

I have shown no mattress associated with the seat section 4, the back section 9 and the side members 15 but one may be used, supported on the spring 23 and it will be seen that this mattress will form the upholstery of the entire device.

From the foregoing, taken in connection

with the accompanying drawings, it will be seen that I have provided an extremely simple and inexpensive, yet a highly efficient and desirable article of furniture, which 5 may be converted for use as a Morris chair, as a lounge, as a full-length bed, or as a relatively short child's bed. Since excellent results may be obtained from the several details disclosed, they are preferably followed.

10 It is to be understood however that within the scope of the invention as claimed, numerous changes may be made.

I claim:

1. A convertible chair comprising a base, a seat section rockably mounted on said base, a back section pivoted to said seat section and movable downwardly to coact therewith in forming a bed, and means for preventing said seat section from rocking when 15 said back section is swung downwardly, comprising a wall rising from and extending transversely across said base in rear of said seat section to support the inner end of said back section.
2. A convertible chair comprising a base, a seat section rockably mounted on said base, a back section pivoted to said seat section and movable downwardly to coact therewith in forming a bed, and an upwardly extending 20 projection on the rear end of said base adapted to support the inner end of said back section when the latter is swung downwardly, whereby to prevent rocking of said seat section.
3. A convertible chair comprising a base, a receptacle rockably mounted on said base and adapted to contain bed clothing, a back section pivoted to the rear upper corners of 25 said receptacle and normally forming a chair back, said back section being movable 30 downwardly to a horizontal position when

the device is to be converted into a bed, a pair of side members receiving said receptacle therebetween and hinged to said receptacle at its upper front corners, the hinge 45 lines of said side members being disposed between the upper and lower edges of the latter, arms carried by the upper edges of said side members, said arms extending rearwardly beyond said side members and having hooks at their lower sides, lugs on the back section normally engaged by said hooks to hold said back section in vertical position and to retain said side members in position to hold said arms horizontally disposed, said side members and arms being 50 adapted to be swung forwardly and downwardly to coact with the back and receptacle in forming a bed, and means on the rear ends of said arms, adjacent said back section, to support said arms and side members when swung downwardly and forwardly.

4. A convertible chair comprising a seat section, a back section hinged to the rear edge of said seat section to fold downwardly 55 and rearwardly, a pair of side members pivoted to the front end of said seat section and adapted to swing downwardly and forwardly, arms carried by the upper edges of said side members and extending rearwardly beyond said members at opposite sides of said back section, the lower edges of the rearwardly extending portions of said arms being provided with front and rear notches, and projections on said back 60 section receivable in either said front or rear notches to adjustably hold said back in either upright or inclined position.

In testimony whereof I have hereunto set my hand.

BENJAMIN C. BARTLEBAUGH.
